EX

OR D 13,972

DESIGN FOR A COOKING-RANGE.

Design No. 13,972, dated June 12, 1883.

UNITED STATES PATENT OFFICE.

H. CLAY BASCOM, OF TROY, AND TOBIAS S. HEISTER, OF LANSINGBURG,
ASSIGNORS TO THE SIMONDS MANUFACTURING COMPANY, OF NEW
YORK, N. Y.

DESIGN FOR A COOKING-RANGE.

SPECIFICATION forming part of Design No. 13,972, dated June 12, 1883.

Application filed April 4, 1883. Term of patent 7 years.

To all whom it may concern:

Be it known that we, H. CLAY BASCOM, a citizen of the United States, residing in the city of Troy, in the county of Rensselaer and

5 State of New York, and TOBIAS S. HEISTER, a citizen of the United States, residing in the village of Lansingburg, in the said county and State, have jointly invented and produced a new and original Design for Cooking-Ranges, 10 of which the following is a specification, reference being had to the accompanying cut, print, or engraving of a cooking-range having said new design.

The general design for the range consists of 15 the upper portion, A, and the lower portion, B, shaped, proportioned, ornamented, and arranged together so as to present the same appearance as is represented in the accompanying print.

20 The design for the upper portion, A, consists of the closet-section C, oven-section D, and recessed section E, severally shaped, ornamented, and arranged together so as to present substantially the same general appearance as is represented in the aforesaid cut.

25 The design for the lower portion, B, consists of the middle part, F, and lateral panels G G, shaped, ornamented, and arranged together so as to have substantially the same appearance as is presented in the aforesaid engraving.

30 The design for the section C consists of the two inner oblong panels, H H, and lateral panels I I, shaped, ornamented, and arranged together substantially as shown in the accompanying cut.

35 The design for the oven-section D consists of the two door-panels J J, middle standard, K, and lateral pilasters L L, shaped, ornamented, and arranged so as to present substantially the same appearance together as shown in the aforesaid print.

40 The design for the recess-section E is composed of the middle panel, M, lateral panels N N', and side panels, O O', shaped, ornamented, and arranged so as to present together substantially the same appearance as a whole as that represented in the aforesaid engraving.

45 The design for the crest-plate P consists of the middle panel, Q, and lateral parts R R, shaped, ornamented, and arranged so as to present together substantially the same gen-

eral appearance as is represented in the aforesaid print.

The design for the panel Q consists of the representation of a buck deer, *a*, between 55 shrub-like trees *b c*, shaped and arranged together, substantially as shown in the aforesaid engraving, on a tablet having a raised border arched in the middle of its top and rectangular at its ends, as shown.

60 The design for the parts R R consists of the scroll ornaments *d d* and end ornaments, *e e*, all shaped, proportioned, and arranged together substantially as shown in the aforesaid cut.

65 The design for the panels H consists of the compound middle ornament, S, and ornamented border *f*, shaped and arranged together substantially as represented in the aforesaid print.

70 The design for the compound ornament S consists of the central rosette, *g*, having radial scroll-prongs, the end ornaments, *h*, and the intermediated ornaments *i*, all shaped, arranged, and connected together as shown in 75 the aforesaid engraving.

75 The design for the panels I and T consists of the central compound ornament, *j*, and ornamental border *k*, all shaped, composed, and arranged together substantially as shown in 80 the accompanying print.

85 The design for the panels J J consists of the compound central ornament, U, and ornamented border V, shaped and arranged together so as to present substantially the same appearance as is represented in the aforesaid cut.

90 The design for the ornament U consists of the lower compound part, *m*, the side scrolls, *n*, and the middle and upper portion, *o*, all shaped, composed, and arranged together as shown in the aforesaid engraving.

95 The design for the pilasters L' L' consists of the compound ornament *p*, surrounded by the arched top ornamented border, *q*, composed, shaped, and arranged together as represented in the aforesaid print.

100 The design for the panel M consists of the representation of a buck deer, *r*, standing with one side to the front and facing in the direction of its length, and between two declivities, *r'*, of which one is in the distance forward of

the deer, and the other is immediately in rear of the deer, and is backed by a cluster of standing tree-trunks having stubs of broken branches, all shaped and disposed so as to present the appearance shown in the aforesaid engraving.

10 The design for the panel N consists of the representation of a woodcock, *s*, with scenery *s'*, shaped and arranged substantially as shown in the aforesaid cut.

15 The design for the panel N' consists of the representation of a snipe, *t*, with scenery *t'*, shaped and disposed substantially as shown in the aforesaid print.

20 The design for the panels O O' consists of the representation of a quail, partridge, or grouse, *u*, and scenery *u'*, shaped and arranged substantially as shown in the accompanying cut.

25 The design for the panels G consists of the compound central ornament, *W*, and ornamental border *V'*, composed, shaped, and arranged together so as to present substantially the same appearance as is represented in the aforesaid print.

30 The design for the ornament W consists of the compound lower portion, *v*, upper part, *v'*, and intermediate portion, *v''*, all shaped and arranged together as represented in the aforesaid cut.

35 The design for the panel-borders V V' consists of the scallop inner beading, *w*, corner ornaments, *w'*, end ornaments, *x*, and middle ornaments, *x'*, all shaped and arranged together as shown in the aforesaid engraving.

40 The design for the fire-door X consists of the series of wide arch-top mica-light apertures *y*, with intervening ornaments *y'*, and the series of narrow draft-apertures *z*, having arched tops and intermediate ornaments, *z'*, all shaped, proportioned, and arranged together substantially as shown in the accompanying print.

What we claim as our joint invention is—

1. The design for a range, composed of the upper and lower portions, A B, shaped, ornamented, and arranged as described and shown.

2. The design for the upper portion, A, composed of the sections C, D, and E, shaped, ornamented, and arranged together as set forth and shown.

3. The design for the portion B, composed of the parts F and G G, shaped, ornamented, and arranged as described and shown.

4. The design for the section C, composed of the parts H H I I, shaped, ornamented, and arranged substantially as set forth.

5. The design for the section D, consisting of the parts J J K L L, shaped, ornamented, and arranged substantially as described.

6. The design for the section E, composed of the panels M N N' O O', shaped, ornamented, and arranged substantially as described.

7. The design for the crest-plate P, com-

posed of the parts Q R R, shaped, ornamented, 65 and arranged substantially as described.

8. The design for the part Q, composed of the representation of a deer, *a*, between trees *b c*, on a tablet having a border arched in the middle of its top and rectangular at its ends, 70 as described and shown.

9. The design for the parts R R, consisting of the ornamental parts *d d* and *e e*, shaped and arranged as described.

10. The design for the panels H H, composed 75 of the compound ornament S and border *f*, shaped and arranged as described.

11. The design for the ornament S, composed of the parts *g h i*, shaped and arranged together as set forth. 80

12. The design for the panels I and T, consisting of the ornamental parts *j* and *k*, shaped and arranged as described.

13. The design for the panels J, composed of the compound ornament U and ornamental 85 border V, as described.

14. The design for the ornament U, composed of the parts *m n o*, shaped and arranged as set forth.

15. The design for the pilasters L' L', composed 90 of the compound ornament *p* and border *q*, all shaped and arranged together as shown.

16. The design for the panel M, composed of the representation of a deer, *r'*, standing 95 between declivities *r*, and in the background standing tree-trunks having stubs of broken branches, as described and shown.

17. The design for the panel N, consisting of the parts *s* and *s'*, shaped and arranged as 100 set forth.

18. The design for the panel N', composed of the parts *t* and *t'*, shaped and arranged as described.

19. The design for the panels O O', consisting 105 of the parts *u* and *u'*, shaped and arranged as specified.

20. The design for the panels G G, consisting of the compound ornament W and border 110 *V'*, shaped and arranged as described.

21. The design for the ornament W, composed of the parts *v v' v''*, all shaped and arranged together as set forth.

22. The design for the panel-borders V V', consisting of the ornamental parts *w w' x x'*, 115 all shaped and arranged together as set forth.

23. The design for the door X, consisting of the parts *y y' z z'*, all shaped and arranged together as described and shown.

In testimony whereof we hereunto set our hands, in the presence of two subscribing witnesses, this 2d day of April, 1883.

H. CLAY BASCOM.
TOBIAS S. HEISTER.
